Primary Examiner — Joseph Kukella*Assistant Examiner* — Darryl J Dardenne*(74) Attorney, Agent, or Firm* — Bochner IP, PLLC;
Andrew D. Bochner(57) **CLAIM**

The ornamental design for a tumbler glass, as shown and described.

DESCRIPTION

FIG. 1 is a top, front, right side perspective view of the tumbler glass;

FIG. 2 is a bottom, rear left, side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

In the drawings, the broken lines are for the purpose of illustrating environment only, and form no part of the claimed design.

1 Claim, 3 Drawing Sheets(56)
